COMBINATION TILE AND SOAP HOLDER

Mary Mildred Wessel, 2810 Meadow Drive, and Marietta
Bowling, 1618 Trevilian Way, both of Louisville, Ky.

Filed Jan. 14, 1963, Ser. No. 73,150

Term of patent 14 years

(Cl. D4—3)

FIG. 1

FIG. 2

FIG. 1 is a front perspective view of a combination tile and soap holder showing our new design;

FIG. 2 is a vertical sectional view taken along lines 2—2 of FIG. 1;

FIG. 3 is a front elevational view thereof.

We claim:

The ornamental design for a combination tile and soap holder as shown.
